UNITED STATES PATENT OFFICE.

WILLIAM W. SPARGO, OF PONTIAC, MICHIGAN.

SCORING APPARATUS.

Application filed August 24, 1925. Serial No. 52,139.

My invention relates to scoring apparatus and an object of my improvements is to provide an improved apparatus for keeping the score in bowling alleys.

- 5 In bowling alleys, there are a plurality of long narrow floors upon which the balls are rolled with chutes at the sides for returning the balls and a clear space for the players, scorers and spectators at one end. 19 Movable boards for supporting the score sheets have been used but these are in the way, generally out of place and apt to be out of repair.

An object of my improvements is to provide an improved apparatus for scoring which shall obviate the above noted objections.

I secure this object in the device illustrated in the accompanying drawings, in 20 which

Figure 1, is a perspective view of a bench which is conveniently placed at the back of the space occupied by the players and spectators. An apparatus embodying my invention is shown adjusted to this bench at the further end and the bench is shown prepared to receive such an apparatus at the end nearest the observer.

Figure 2, is a section on the line II—II 39 of Figure 1.

Figure 3, is a detail plan view to an enlarged scale looking from the position indicated by the feathered arrow 3^a, Fig. 2.

Figure 4, is a detail sectional view in the 35 plane indicated by the line IV—IV, Figure 2.

Figure 5, is a detail section on the line V—V of Figure 2.

Figure 6, is a perspective view of a modified form of the casting to be adjusted to the back of the bench a.

Figure 7, is a plan view of the casting for supporting the uprights.

Figure 8, is a sectional elevation similar 45 to Figure 3, and using the casting shown in Figure 6, the section being taken through the slot a⁴, and the table folded up out of the way behind the bench.

a, indicates the bench as a whole, of which 50 a² is the seat and a³ the back. In the back a³ toward each end thereof, I cut a slot a⁴ in from the upper edge thereof, and extending from $\frac{1}{3}$ to $\frac{1}{2}$ of the height of the back. b, b, are aluminum castings of similar form 55 having slots b³, b⁴, therein, adapted to fit over the back a³ of the seat at the edges of

the slots a⁴. b⁴, b⁴, are flanges or ribs extending rearwardly from the castings b, b, with their back edges parallel and vertical. b², are vertical slots cut in the inner surfaces of the flanges b⁴, b⁴. c, indicates through-bolts by which the castings b are secured to the seat back a³. d, is an aluminum block extending between the inner surfaces of the castings b, b, and provided with laterally extending flanges d², d² which engage and slide in the slots b². d³, is a cylindrical stem extending downward from the lower end of the block d.

e, is a casting or plate adapted to be 70 screwed on the back a³ of the seat a and provided with a projection e² which extends horizontally backward from below the slot a⁴ and the space between the inner faces of the casting b, b. e³ and e⁴ are cylindrical apertures extending vertically through the projection e². The stem d⁴ of the block d extends through the aperture or opening e⁴ and is clamped therein by a thumb screw e⁵.

f, is a cylindrical rod fitting in and extending through the aperture e³ adapted to be adjusted to the different heights through said aperture. The rod f may be clamped to its adjusted position by a thumb screw e⁵.

g, is a cylindrical rod pivoted at one end to the upper end of the rod f so as to swing in a vertical plane through the axes of said rods. A convenient hinge construction fg is shown joining the rods f and g, the outer end of the rod g is bent at right angles, as shown at g² in Figures 1 and 5. The rod g² 90 may pass into the slot a⁴ between the castings b, b.

j, is a fitting sleeved upon the part g² of the rod or tube g and provided with a 95 turned projection j² (Fig. 5) extending at right angles to the part g² of the rod g. h, is a table for receiving the score sheet. h², is a clamp by which the score sheet is held down upon the table. h³, is a ridge extending along one edge and above the upper surface of the table h. h², is a spider secured to the lower surface of the table h and having a central aperture h³ therein which fits over the projections j² of the fitting j. h⁴ 100 (Fig. 2) is a thumb screw by which the spider h is clamped to the projection j², and j³, is a thumb screw for clamping the fitting j to its adjusted position upon the part g².

The turning of the fitting j about the part g² and the spider h² and table h about the projection j² forms a universal joint for the

table *h* so that the table can be adjusted to any position required and fixed in that position.

In the ordinary use of the table, the rod *f* is adjusted to the height required and clamped in position by a thumb screw *e*⁵. The angular position of the fitting *j* is then fixed by adjusting the stem *d*³ of the block *d* up or down and clamping it by a thumb screw similar to *e*⁵. The rod *g* rests upon the upper edge of the block *d* in a cavity *dg* formed to the shape of said rod, as shown most distinctly in Figure 4.

In this position, the score sheet would be laid upon the table *h* and held there by a clamp *h*⁶. The scorer would sit upon the bench and write on the score sheet as required. If he should wish to score while standing up, the table would be turned to the position shown in broken lines at the right of Figure 2, the angle of the rod *g* perhaps being elevated so that all he would have to do is to step up toward the bench and record the score.

If a match is being played and a special scorer is provided, the rod *f* may be pressed down through the aperture in the projection *e*² until it comes near the floor, the rod *g* then coming within said aperture in a vertical position holding the score board *h* in the position indicated by the dotted lines at the left of Figure 2. The scorer would stand back of the bench *a* in this case with the score board located directly in front of him; in this position the rod *f* would be vertical with its lower end resting upon the floor, so that it shall act as a support for the apparatus.

As an alternative form of construction, the castings *b*, *b*, may be replaced by a single integral casting *ba* (Fig. 6) having the joining portion *ba*² and omitting the fin or ridge *b*⁴. In this case, the flanges *d*², *d*², of the block *d* may be omitted.

The rods *f* and *g*, *g*², may be made of commercial piping.

When not in use, the table and supporting apparatus may be placed in the position shown in Figure 8 with the table back of the bench and the rod *f* turned under the same.

What I claim is:

1. In an apparatus of the kind described, the combination of a bench having a back with a vertical slot formed therein from its upper edge, a casting engaging each edge of said slot to strengthen the same and extending backward therefrom, said castings being provided with opposite vertical slots back of said bench, a block engaging and adapted to slide in said vertical slots, a part secured to said bench beneath the slot in the back there-

of and extending backward therefrom and having a vertical aperture therethrough, a rod passing through and adapted to reciprocate in said aperture, said part being so located that said rod shall be parallel and back of said block, a second rod jointed at its inner end to the upper end of the first named rod and adapted to enter laterally into the slot in the back of the bench, and an adjustable table on the outer end of said second rod.

2. In an apparatus of the kind described, the combination of a bench having a back with a vertical slot formed therein from its upper edge, a part secured to said bench below said slot and extending backward therefrom, said part being provided with a vertical aperture therethrough, a rod fitting and adapted to reciprocate in said aperture, a second rod having its inner end jointed to the upper end of the first named rod adapted to pass laterally into said slot, and a table adjustably secured at the outer end of the second rod.

3. In an apparatus of the kind described, the combination of a bench having a back with a vertical slot formed therein from its upper edge, a part secured to said bench below said slot and extending backward therefrom, said part being provided with a vertical aperture therethrough, a rod fitting and adapted to reciprocate in said aperture, a second rod having its inner end jointed to the upper end of the first named rod adapted to pass laterally into said slot, and a table adjustably secured at the outer end of the second rod, said second rod and the joint between said rods being adapted to travel in said aperture.

4. In an apparatus of the kind described, the combination of a bench having a back with a vertical slot formed therein from its upper edge, a part secured to said bench below said slot and extending backward therefrom, said part being provided with a vertical aperture therethrough, a rod fitting and adapted to reciprocate in said aperture, a second rod having its inner end jointed to the upper end of the first named rod adapted to pass laterally into said slot, and a table adjustably secured at the outer end of the second rod, the joint between said rods being adapted to pass through said aperture and said second rod being adapted to fit in said aperture with the first mentioned rod extending vertically with its lower end resting upon the floor.

In testimony whereof, I sign this specification.

WILLIAM W. SPARGO.
